S. LARSON

WINDOW OR TRANSOM HINGE

Filed Feb. 16, 1924

Fig. 1.

UNITED STATES PATENT OFFICE.

SHURE LARSON, OF NORWAY, IOWA.

WINDOW OR TRANSOM HINGE.

Application filed February 16, 1924. Serial No. 693,243.

The object of this invention is to provide a hinge for windows, transoms and the like, which may serve both as a hinge and a support for the window or transom when open.

• The invention is fully disclosed in the description and claim following, reference being had to the accompanying drawing, in which:—

Fig. 1 is a view in perspective illustrating 10 a cellar window with the improved hinges attached. Fig. 2 is a side view of the hinge, with a fragment of sash attached. Fig. 3 is a front view of the same, but showing some modification in structure.

15 In the drawing, the numeral 5 denotes a cellar window sash, such windows being usually hinged at the top so as to swing inwardly and upwardly. The common means of support for the sash when so raised is a 20 hook and eye holding the window in the single wide open position. In deep cellars this fastening is so high as to require a step for the operator, and the use of both hands in hooking up the window. Hooks or buttons are also required for fastening the window in closed position. The hinges now 25 to be described are adapted to lock the window in closed position, as well as to support it at any desired open position.

30 In the drawing, the numeral 6 designates the hinge member which is secured to the window frame 7. This comprises a wall-plate 8 suitably provided with holes 9 for fastening screws 10, and a quadrant-shaped wing 11 disposed at right angles to the wall-plate. The other member has a similar 35 wall-plate 12, with screw-holes 13, and a lesser wing 14 also at right angles to the base. Near the upper end this wing is pierced, as is the other member near its upper and inner angle, for a pivot 15, which is preferably a small bolt that may be easily removed when it is desired to take out the window sash. The lower end of the wing 14 40 is formed as a stirrup 16 to engage the curved edge of the quadrant, as shown. Holes at 17, which are in register when the window is closed, serve for the locking of the window by pins or nails 18.

45 In the detail figures of the drawing I have shown a plurality of means for holding the window open by friction. In Fig. 2

this is effected by the wedging action of the quadrant edge in the loop of the stirrup. The dotted line in this figure indicates an 55 arc of which the pivot is the center, showing that the pivot is set a little off-center with respect to the curve of the wing. It is evident that the raising of the sash will serve to wedge the parts of the hinge together, 60 and the friction of the parts so wedged is sufficient to support the sash. As shown in Fig. 2 this support would be mainly effective when the sash is completely elevated. In Fig. 3, however, the friction applies to the 65 hole curve of the quadrant, and the sash is supported at any point of elevation. In this case the stirrup, which should be slightly elastic, is made to pinch the quadrant with enough frictional effect to support the sash. 70 For this purpose the stirrup may be provided with a tension bolt 19. A corrugated edge 20 for the quadrant enhances the grip of the stirrup, but is not indispensable, as sufficient tension may be obtained on a plane 75 surfaced wing, as shown in the other figures of the drawing.

The hinge members are preferably formed of thick sheet steel, and for use in cellars or other damp places should be suitably protected from rust, as by galvanizing. 80

Having thus described my invention, I claim:

In a hinge, a fixed member consisting of a 85 plate adapted to be fixed to a window frame and a quadrant shaped wing outstanding from the plate at right angles thereto, a movable member consisting of a plate adapted to be fixed to a sash pivoted in the frame and an outstanding quadrant shaped wing disposed at right angles to the plate thereof, the second wing being pivoted at its axis to the axis of the first wing to be off center thereof, a U-shaped stirrup fixed to the edge of the second wing and straddling the edge of the first wing so that its free end frictionally engages therewith, a bolt extending through the sides of the stirrup to adjust the frictional engagement of the 90 free end of the stirrup with the edge of the first wing.

In testimony whereof I affix my signature.

SHURE LARSON.
